SASH LIFT

Roland V. Fowler, Rockford, Ill., assignor to Amerock Corporation, Rockford, Ill., a corporation of Connecticut

Filed Apr. 8, 1968, Ser. No. 11,351

Term of patent 14 years

(Cl. D10—10)

FIG. 2 is a top view of the sash lift.

FIG. 3 is a perspective view of the sash lift.

FIG. 4 is a side view as seen from the right of FIG. 1.

FIG. 5 is a sectional view taken along the line 5—5 in FIG. 1.

FIG. 6 is a sectional view taken along the line 6—6 in FIG. 1.

I claim:

The ornamental design for a sash lift, as shown.
